OIL BURNER

Filed March 24, 1924

2 Sheets-Sheet 2

Fig. 3.

UNITED STATES PATENT OFFICE.

CHARLES M. COLVIN, OF WILMETTE, ILLINOIS.

OIL BURNER.

Application filed March 24, 1924. Serial No. 701,432.

My invention relates to the general art of burners, and belongs more particularly to that class known as oil or hydrocarbon burners, adapted for use wherever found applicable. The invention has among its objects the production of a burner and system of the kind described that is simple, compact, durable, reliable, efficient and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a view in elevation illustrating my burner and apparatus adapted to be used in connection therewith;

Fig. 2 is a sectional view of the burner taken substantially on line 2—2 of Fig. 3;

Fig. 3 is a top plan view of the same, with the baffle removed; and

Fig. 4 is a sectional view taken substantially on line 4—4 of Fig. 3.

Referring to the drawings, in which the preferred embodiment of my invention is shown, 1 represents a chambered part preferably provided with the two chambers 2 and 3 separated by the partition or web 4 and a central part which is provided with an opening through the same. The member 1 is recessed as indicated at 5 about the opening, and the pipe 6 positioned therein, so that a chamber 8 is formed, the top side being closed by the member 7. The member 6 is shown formed with openings 9 therethrough communicating with the chamber

8. The member 1 is preferably supported on an apertured plate 10 having a flange 11 about the same, the lugs 12 on one part maintaining the parts in spaced relation. As shown, the plate 10 is provided with an opening 16 at the middle extending substantially from side to side, 15 being a flange about the same. This flange is preferably of such height that it seats against the bottom of member 1.

Extending to the burner is a feed pipe 17 of the desired size, which extends to a source

of oil supply. Arranged within the feed pipe 17 is a feed pipe 18, 19 being material such as asbestos or the like which forms a filler about the pipe 18 and centers the same.

When oil is fed to the pipe 17, which is connected with the chamber 2, the same may flow freely through the pipe 18 to the chamber. A portion of the oil can seep through the packing 19 at the outside of pipe 18, capillary attraction as well as a slight head on the oil tending to cause a portion of the oil to travel into the chamber in this manner. The part 1 being hot by virtue of the burning oil vapor, as hereinafter described, the oil is vaporized in chamber 2 and discharged through the pipe 24, as will be hereinafter described.

It may be mentioned that the pipe 24, 75 preferably extends into the chamber 2, as indicated at 25.

Extended to chamber 3 is a water pipe 21, within which is arranged a pipe 22, 23 representing packing material or filling such as asbestos or the like. The flow of water through the pipe 22 and packing 23 is similar to the passage of oil to the chamber 2. A discharge pipe 29, which preferably projects to the interior of the chamber 3, as indicated at 30, extends from the chamber to a point below the opening in the burner previously described.

Referring particularly to Fig. 4, pipe 24 extends below the sleeve 6 as shown, and is 90 constructed with a port 27 and opening 28, the end being closed by the plug 26. The pipe 29 projects below the pipe 24 and is provided with a discharge port 33 adjacent the opening 28 in the pipe 24, the end of the pipe being closed by a plug 31, and an opening opposite the port 33 is closed by the plug 32.

Generally, I prefer to arrange a baffle plate or spreader 34 above the burner opening, the same being supported or maintained in place in any suitable manner. As shown, the same is suspended from a chain or other connector 35 from a cross-bar 37 which may be supported by the standards 36. Obviously, any equivalent means for supporting the spreader plate 34 may be employed.

In Fig. 1, I have illustrated more or less diagrammatically the burner installed in a furnace or boiler 39. It may be mentioned that the boiler, furnace or heater may be of any preferred construction, the same in it-

self forming no part of the present invention. The arrangement and particular installation of the burner within the boiler or the like may, of course, vary with different installations, but on the whole the installations are more or less similar. As illustrated, 40 represents the grates or any equivalent support, and 41 preferably an annular ring shaped base surrounding the burner 10 but with a space therebetween and preferably of fire brick, cement or the like. I have shown the fuel pipe 17 connected with the fuel tank 42, and the water pipe 21 connected with a source of water supply, for example, tank 54. In the particular installation illustrated, a pipe 43 extends from the tank 42 to an auxiliary tank 44 which is constructed so as to maintain a substantially constant head of oil, whereby the feeding to 20 the burner is uniform. I have not shown details of construction of this auxiliary tank as the same may be modified more or less as desired. It may be mentioned, however, that as shown, a float 45 controls the admission 25 of oil to the tank, 46 being an automatic drip valve which will cut off the supply in the event there is any leakage of oil. The pipe 49 connected with the tank 44 and pipe 17 may be provided with suitable valves, for 30 example, as indicated at 48. I have shown diagrammatically a filter 47 arranged within tank 44, which will strain the oil fed to the burner. I have shown a drip pan 50 arranged below the burner and arranged to 35 discharge into a shut-off valve cup 51 connected with the valve 52, so that in the event there is any leakage of oil from the burner, instead of flooding, the same will automatically shut off the supply, thereby preventing possible fire hazard as well as 40 unpleasant flooding of the boiler room. Any type of automatic shut-off may be used, that shown being merely for illustration.

The water feed pipe 53 from the water 45 mains is connected with the tank 54, and it may be mentioned that I prefer to maintain in the tank an air cushion so that the level of the water is substantially below the top of the tank, the same being shown for 50 purposes of illustration as at 57. I also prefer to extend the pipe 55 to adjacent the bottom of the tank and provide a filter or strainer 56. Such shut-off valves and other apparatus as desired may be employed.

55 The operation of the device may be briefly described as follows: Oil is fed to the burner through pipe 17 at substantially an even pressure or rate of flow, and water is fed to the burner through pipe 21 also at a 60 substantially constant pressure or rate of flow, it being possible by means of the various valves to control the rates of flow as desired. I have not endeavored to illustrate the several controlling valves 65 in detail, but it may be mentioned that

these may be so arranged that they will operate in unison and in a predetermined manner so that variation of the oil feed will cause a variation of the water feed. In starting the burner in operation, oil or other combustible fuel may be placed on the plate 10 and ignited. This will cause the part 1 to be heated up and become hot so that when oil and water are admitted to the chambers 2 and 3 respectively, the same will be vaporized and a pressure generated, causing the same to be discharged into the pipes 24 and 29. Steam will be discharged through the port 33 and opening 28 and with oil vapors through 27 into the opening or bore of the sleeve 6, and when ignited will burn at the outer end of the tube 6 with an intense heat. The same will be deflected out under the spreader 34 and strike the inner walls of the boiler or furnace. The vaporized steam and oil will carry air from below the burner up with it, thereby affording perfect combustion. I have found that by providing the chamber 8 with the ports 9, that the flame will not run down into the tubular opening of the burner but will be always maintained at the top where it should be. Of course, after the burner is in operation, the same becomes intensely hot so that the vaporizing in the chambers 2 and 3 becomes complete. However, the admission of the oil and water to the chamber and the constant vaporizing therein prevents the burner from becoming excessively hot. I have found that by providing the packing 19 and 23 about the feed pipes 18 and 22, that the pipes are prevented from getting excessively hot as the oil or water passing up through the packing tends to maintain these pipes cooler than would otherwise be the case if the packing was omitted. The result is that boiling of the oil and carbonizing of the same in the pipe 18 is prevented and resulting trouble eliminated. Likewise, the water will not boil in pipe 22, and the deposit of lime, etc., is prevented. The result is that the burner will function and operate perfectly and efficiently for long periods of time without cleaning. It will be noted that there are no small ports or openings which may easily and quickly clog up or carbonize, thereby causing trouble as well as lowering the efficiency of the device.

It has been found by use that the burner will operate with a minimum of attention, that regulation is comparatively simple so that automatic regulators or thermostatic regulators may be employed and efficient results secured.

Having thus described my invention, it is obvious that various immaterial modifications may be made in the same without departing from the spirit of my invention; hence I do not wish to be understood as limiting myself to the exact form, construction,

arrangement and combination of parts herein shown and described or uses mentioned.

What I claim as new and desire to secure by Letters Patent is:

5 1. In a device of the kind described and in combination, a plate provided with a flange about the exterior thereof and with a central flanged opening, a burner member mounted thereon having a central opening 10 and provided with a plurality of chambers, an oil feed pipe to one chamber and a water pipe to another chamber, said pipes extending through said plate opening, a discharge pipe from each chamber extended to below 15 the central opening in the burner member and provided with ports arranged to discharge comingled oil and water vapors into the burner opening.

2. In a device of the kind described and 20 in combination, a plate provided with a flange about the exterior thereof and with a simple flanged opening, a burner member mounted thereon having a central opening and formed with three chambers, an oil feed 25 pipe for one of said chambers, a water feed pipe for another of said chambers, said pipes extending through said plate opening, a discharge pipe extending from the chamber having the oil feed pipe, a second discharge 30 pipe from the chamber having the water feed pipe, said discharge pipes extending to a position below the central opening in the burner member and provided with ports arranged to discharge co-mingled oil and 35 water vapors into the burner opening, the third chamber communicating with the central opening in the burner adjacent the top thereof.

3. In a device of the kind described and 40 in combination, a plate provided with a flange about the exterior thereof and with a central flanged opening, a burner member mounted thereon having a central opening and provided with three chambers, an oil 45 feed pipe arranged to discharge into one of said chambers, a water feed pipe arranged to discharge into another of said chambers, said pipes extending through said plate opening, a discharge pipe for the chamber having the oil feed pipe, a second discharge pipe for the chamber having the water feed pipe, said discharge pipes arranged to discharge comingled oil and water vapors into the burner opening from a point below said 50 opening, the third chamber communicating with the interior of the central opening through the burner adjacent the upper end thereof, and a spreader plate arranged above said opening.

4. In a burner of the kind described and 55 in combination, a member provided with a central opening and with a plurality of vaporizing chambers, a pipe extending from one chamber to a point below the burner and provided with openings on opposite

sides at the center line of said central opening and below said central opening, and a second pipe from the other chamber extending below the burner to a point on the center line of said central opening at a point 70 below the other pipe, and having a discharge port in alignment with the openings in said first-mentioned pipe.

5. In a burner of the kind described and 75 in combination, a member provided with a central opening and with a plurality of vaporizing chambers, a pipe extending from one chamber to a point below the burner and provided with main openings on opposite sides at the center line of said central opening, a second pipe from the other chamber extending below the burner to a point on the center line of said central opening at a point 80 below the other pipe, and having a discharge port in alignment with the openings in said first-mentioned pipe, said member provided with a chamber adjacent the top of and surrounding said opening and provided with ports opening into the central 85 opening.

6. In a device of the kind described and 90 in combination, a burner member consisting of a circular member provided with a central aperture and having a plurality of 95 chambers, conduits extending to said chambers, each consisting of a conduit with an inner pipe arranged centrally therein with heat-resisting porous packing material between the two, and discharge pipes extending from said chambers below the burner to said central opening, and provided with discharge ports in alignment with the center of the opening, the top pipe having an opening at the under side in alignment with said 100 other ports.

7. In a burner of the kind described and 105 in combination, a burner member consisting of a circular member provided with a central aperture and having a plurality of 110 chambers, a pipe extending to each of said chambers, each consisting of a pipe with an inner pipe arranged therein with heat-resisting porous packing material between and spacing the two, and discharge pipes extending from said chambers below the burner at said central opening, and provided with discharge ports in alignment with the center of the opening, the top pipe having an opening at the under side in alignment with said 115 other ports.

8. In a burner of the kind described and 120 in combination, a burner member consisting of a circular member provided with a central aperture and having a plurality of 125 chambers, a pipe extending to each of said chambers, each consisting of a pipe with an inner pipe arranged therein with heat-resisting porous packing material between and spacing the two, and discharge pipes extending from said chambers below the 130

burner at said central opening, and provided with discharge ports in alignment with the center of the opening, the top pipe having an opening at the under side in alignment with said other ports, a flanged plate for supporting said burner member provided with a central flanged opening for said feed and discharge pipes and permitting the passage of air to the lower end of the burner opening, and a spreader plate mounted above the burner.

9. In a burner of the kind described and in combination, a burner member consisting of a circular member provided with a central aperture and having a plurality of chambers, a pipe extending to each of said chambers, each consisting of a pipe with an inner pipe arranged therein with heat-resisting porous packing material between and spacing the two, and discharge pipes extending from said chambers below the burner at said central opening, and provided with discharge ports in alignment with the center of the opening, the top pipe having an opening at the under side in alignment with said other ports, a flanged plate for supporting said burner member provided with a central flanged opening for said feed and discharge pipes and permitting the passage of air to the lower end of the burner opening, and a spreader plate mounted above the burner, and means for supplying oil and water to said burner at substantially a constant pressure head.

10. A burner having a plurality of vaporizing chambers, a plate arranged thereunder provided with an opening for the passage of air to the burner and having a flange about the opening extending between the burner and plate, means for supplying fuel to one of the chambers, means for supplying water to the other of the chambers, and means disposed in the last-mentioned opening and communicating with the chambers for supplying vaporized water and fuel to the burner opening.

11. A burner member, a plate member arranged thereunder flanged about the periphery thereof and provided with an opening for the passage of air to the burner, a flange on one of said members and contacting with the other, said flange substantially constituting an air conduit, a plurality of vaporizing chambers, and a plurality of means disposed in said air conduit and communicating with the vaporizing chambers for supplying vaporized matter to the burner member.

12. A burner member, a plate member arranged thereunder and provided with an opening for the passage of air to the burner, a flange on one of said members and contacting with the other, said flange substantially constituting an air conduit, and con-

duits in said conduit extending to and from the burner, a plurality of vaporizing chambers operatively disposed with respect to the burner member, means for supplying water to one of said chambers, means for supplying fuel to the other of said chambers, and means disposed in said air conduit and communicating with the chambers for supplying vaporized water and fuel to the burner member.

13. A burner having a passage therethrough and comprising an oil vaporizing chamber in close proximity to said passage, said passage terminating at one end in a flame orifice, a tube having one end communicating with the oil vaporizing chamber and having its other end spaced from said passage, said latter end of the tube being provided with a port whereby vaporized oil is projected into the passage at the end thereof opposite the flame orifice, and a second chamber adjacent the flame orifice end of said passage and communicating directly with the interior of the passage.

14. In a burner of the class described and in combination, a burner member including a circular member having a central opening and formed with a recess around said opening, a pipe extending up through the opening above the top of the circular member and formed with a plurality of openings, and a closure member fitted around and embracing the upper end of the pipe for closing the recess.

15. In a burner of the class described and in combination, a burner member including a circular member having a central opening and formed with a recess around said opening, a pipe extending up through the opening above the top of the circular member and formed with a plurality of openings, a closure member fitted around and embracing the upper end of the pipe for closing the recess, and a baffle member suspended above the closure member in spaced relation therewith.

16. In a burner of the class described and in combination, a burner member including a circular member having a central opening and formed with a recess around said opening, a pipe extending up through the opening above the top of the circular member and formed with a plurality of openings, a closure member fitted around and embracing the upper end of the pipe for closing the recess, and a baffle member suspended above the closure member in spaced relation therewith and having its upper surface flush with the upper end of the pipe.

In testimony whereof, I have hereunto signed my name.

CHARLES M. COLVIN.
